PACKLESS VALVE STRUCTURE FOR TOILET TANKS

Eisto D. Park, Frankfort, Ind., assignor to The Indiana Brass Company, Frankfort, Ind., a corporation

Original application July 14, 1939, Serial No. 284,432, now Patent No. 2,229,601, dated January 21, 1941. Divided and this application June 22, 1940, Serial No. 341,820

7 Claims. (Cl. 137—104)

This invention relates to a supply fixture and more particularly the valve structure thereof and for toilet storage tanks.

This application is a division of the copending application, Serial No. 284,432, filed July 14, 1939, and entitled "Antisiphon, nonsplashing valve structure," and now Patent No. 2,229,601, granted Jan. 21, 1941.

The chief object of this invention is to provide 10 a toilet storage tank fixture wherein the valve is of packless character and so arranged that it is substantially free from leakage, and especially free from splashing and squirting commonly characteristic of so-called packless valves. 15 The chief feature of this invention is to provide a valve structure arranged whereby water discharged under pressure creates a suction which is so associated with the packless valve member that leakage, as aforesaid, is eliminated and thus 20 spraying or splashing of the storage tank cover does not occur.

Another feature of the invention is that a valve 25 of this character shuts off at higher pressures than valves of this common characteristic employ.

Other objects and features of the invention will be set forth more fully hereinafter.

The full nature of the invention will be understood from the accompanying drawing, the following description and claims:

In the drawing, Fig. 1 is a front elevational view of the embodiment of the invention in association with a toilet tank arrangement, the latter being shown in section and with cover removed.

Fig. 2 is an enlarged central sectional view of the invention and associated fixture parts.

Fig. 3 is a top plan view thereof.

In the drawing, 10 indicates a toilet storage tank. A pressure supply line 11 is suitably connected as at 12 to a riser structure 13, the latter extending through the tank 10 and being suitably sealed thereto as indicated at 13a. The upper end of the riser 13, see Fig. 2, is threaded as at 14 to receive a member 15 having an externally threaded portion 16 and a nozzle portion 17, the latter terminating in a suitably formed end portion 18 which defines a discharge passage 19 that extends through the member 15 and is in free communication with the riser 13.

A body portion 20 having a chamber 21 adjacent the discharge nozzle 18 and surrounding the upwardly extending portion 17 of the member 15 has threaded connection as at 22 with the 55 threaded portion 16 of the member 15. This con-

stitutes the support for the supply and control fixture.

The chamber 21 communicates with a superposed chamber 23 also formed in the member 20 and by means of a tapered passage 24. The upper end of the chamber 23 is closed by a plug or closure 25 having threaded engagement with the upper portion of the body casting and in axial alignment with the above described parts. This closure 25 terminates at its lower end in a frustoconical, preferably complementarily formed portion 27. The seat 24 and valve portion 27, when properly spaced apart, provide a conically directed channel, providing a communication of regulated amount between the chamber 21 and 15 the chamber 23, the regulation being obtainable, as now set forth.

The outer end of the closure 25, integral with the control valve 27, is provided with a lateral flange 28. The body portion includes a projecting flange 29, see Fig. 2, apertured as at 30 to receive a retaining bolt 31, the head of which overlies the flange 28 of the valve and closure member. This member 25—27 constitutes a closure for the chamber 23 together with a valve 25 member for controlling the communication between the chambers 21 and 23.

The member 25 has a bore 32 therein. This is of cylindrical character and slidably mounted therein is a valve member which is of packless 30 character. This valve member is of multi-part character. It includes a head portion 33 and a stem portion 35, the lower end of which is enlarged as at 35a. The stem and head portions have a threaded connection 33a therebetween, 35 see Fig. 2. The enlargement 35a is externally threaded as at 36 to receive a threaded sleeve 37 having an inwardly tapered flange 38. Between the face 39 of this valve construction and the flange portion 38 is positioned a seal or valve 40 member 40, the same being retained upon the plunger or multi-part valve by the flange 38 and the face 39. The seal 40 is movable therewith.

This plunger structure includes an upwardly directed portion 41 slotted as at 42 to receive 45 an arm 43 of a lever member 44 pivotally supported at 45 by means of a thumb screw 46 which is mounted in the spaced ears 47 integral with an upwardly directed and lateral portion 48 of the body portion 20.

Included within said upwardly and laterally directed portion 48 is a supply passage 49 which, at its lower end, communicates with the chamber 23 as shown in Fig. 2. The body portion of the member 25 herein is shown provided with ports 55

90 that lead to the interior or bore in which the plunger is reciprocally mounted. This bore 32 mounts a lower ring member 81 apertured as at 82 and an upper ring member 83 apertured as at 84, the two ring or washer-like members being positioned in spaced relation and forming therebetween a chamber 85 within the bore 32. The stem portion 35 of the plunger is slidably supported in the apertures 82 and 84, the ring members 81 and 83 being press fitted into the bore 32 and being relatively rigid therewith.

Now, when the lever 44 is actuated to elevate the plunger structure water under pressure discharges from the passage 18 into the chamber 21. The majority of the water then discharges through the conical passage into the chamber 23 and then discharges upwardly through the passage 48. Some of the water under pressure in chamber 21 will pass upwardly between the sleeve 37 and into the bore 32; and from thence it will pass through the lowermost ring member at the aperture 82 and into the bore chamber 85.

Such water as does pass into this chamber 85 due to the discharge of water through passage 48 is subject to suction applied to the ports 86 and thus the chamber 85 is a region of low pressure instead of being a region of high pressure such as chamber 21. Consequently, little if any, water will discharge through the aperture 84 below the enlarged portion or head 33 of the plunger structure and within the member 25.

Thus, the water will not spray or squirt upwardly because in most instances there will be no escape of water into this chamber last mentioned 35 and such that does or may escape will be under substantially little or no pressure and should any escape under slight pressure, it will immediately flow along the stem portion 35 and engage the under-face of the head 33 and thus be baffled or laterally directed.

The upper and remote end of the passage 48 communicates with a chamber 50 formed in an enlargement 51 integral with the upwardly directed portion 48 of the body casting. Projecting from the enlargement 51 is a pair of ears 52 and the same pivotally support as at 54 a lever 55. This lever terminates in a threaded socket 56 adapted to receive an arm 57 in the form of a rod, or the like, that threadedly supports a float 58. The lever 55 between the connection 56 and the pivotal support 54 is connected to a dual link structure 59 connected together as at 60. This link structure is pivotally connected to the float mechanism as at 61 and is pivotally connected as at 62 to an outer free end of the lever 44.

Extending outwardly from the chamber 50 is a tubular portion 63—see Fig. 1—which supports a tube 64 that discharges into the overflow pipe 65 common to all toilet storage tanks. This overflow pipe discharges to the conduit 66 below the usual manual control "ball" valve. The conduit 66 communicates freely with an intake structure fixture 67 normally. This fixture 67 is maintained in closed position by the rubber ball-like valve 68 carried by the lower end of the rod 69, slidably supported in the guide 70 adjustably supported on the overflow pipe discharges to the conduit 66 below the usual manual control "ball" valve. The conduit 66 communicates freely with an intake structure fixture 67 normally. This fixture 67 is maintained in closed position by the rubber ball-like valve 68 carried by the lower end of the rod 69, slidably supported in the guide 70 adjustably supported

on the overflow tube 65 as at 71. An actuating mechanism of conventional character common to structures of this general type, includes the lifter member 72 and the head portion 73 of the rod 69 bears on the lateral portion of said lifter 5 member.

It will be noted that as long as water is being supplied to the chamber 23 in regulated amount by means of the adjustment previously mentioned, water will discharge into the chamber 50 10 and a relatively small amount of this water will discharge through tube 64 into the overflow tube 65 and thence to the line 66.

After the tank has been filled to the level indicated by the dotted line determined by float 15 valve adjustment and the manual member is operated, the rubber ball valve 68 is elevated and the water discharges from the tank into the toilet bowl proper and flushes the bowl. In the event such flushing syphons the water out of 20 the trap normally beyond or included in the bowl, the water discharged by line 64 into the overflow 65 upon closure of the valve 68, supplies water to the bowl and especially the trap portion thereof to water seal the same. This 25 prevents the venting to the bowl of the undesirable odors that might be present in the waste pipe or line from the toilet fixture.

Another protective feature of the present invention is as follows: Should the pressure in the 30 supply line 13 be sufficiently great in co-relation to the degree of opening between the conical member 25 and the seat 27 there is created a considerable degree of vacuum in the chamber 85 so that air is drawn into the chamber through 35 the aperture 84.

While the invention has been illustrated and described in great detail in the drawing and foregoing description, the same is to be considered as illustrative and not restrictive in character.

The several modifications described herein, as well as others which will readily suggest themselves to persons skilled in this art, are all considered to be within the broad scope of the invention, reference being had to the appended claims.

The invention claimed is:

1. In a toilet tank fixture, the combination with a pressure supply member, and a valve controlling the discharge therefrom, of a body having a pair of chambers therein having a single constant communication therebetween, means within the body regulating said single constant communication between chambers, the member discharging to one chamber, and the other chamber having a discharge, chamber forming means within the communication regulating means, and a valve operating member slidably supported by the chamber forming means, the third mentioned chamber communicating with said other chamber for the purpose described.

2. A fixture as defined by claim 1, characterized by the body and the regulating means having an adjustable connection therebetween.

3. A fixture as defined by claim 1, characterized by the body and the regulating means having an adjustable connection therebetween, and means for securing the regulating means to the body in the adjusted position.

4. In a valve structure for a toilet tank, the combination of a valve body having a vertical bore therethrough with an intermediate restriction forming two superposed chambers, a discharge passage from the upper chamber, a pressure water supply to the lower chamber having 75

- an upwardly directed tubular valve seat in the lower chamber, a valve member therefor including a stem structure in the bore and extending upwardly therefrom and projecting above the bore for vertical reciprocation, means adjustably mounted in the bore and having a portion in juxtaposition to the bore restriction for regulating chamber communication, and chamber forming means in the last mentioned means forming a chamber communicating with the upper chamber, said chamber forming means slidably supporting and exposing said stem structure to the third mentioned chamber.
5. A valve structure as defined by claim 4, characterized by the chamber forming means constituting a packless support and bearing for the stem structure.
6. A valve structure as defined by claim 4, characterized by the chamber forming means comprising a pair of spaced washer-like mem-

bers, the stem structure being slidable therein and forming with said members the third mentioned chamber.

7. A valve arrangement for a toilet tank and the like including a body having a pair of superposed chambers therein having a single constant communication therebetween, means within the body regulating said single constant communication between the chambers, the lower chamber being adapted or arranged for connection to a pressure supply, the upper chamber having a discharge discharging upwardly therefrom, chamber forming means within the regulating means, a valve controlling the connection to the lower chamber for controlling the discharge thereto, and a valve operating member slidably supported by the chamber forming means, the third mentioned chamber communicating with said upper chamber for the purpose described.
